UNITED STATES PATENT OFFICE.

EDWIN ORLANDO BLACKWELL, OF WYNYARD, TASMANIA, AUSTRALIA.

SHIP-VENTILATOR AND CONNECTIONS THERETO.

No. 914,230.

Specification of Letters Patent.

Patented March 2, 1909.

Application filed June 13, 1908. Serial No. 438,391.

To all whom it may concern:

Be it known that I, EDWIN ORLANDO BLACKWELL, a subject of the King of Great Britain and Ireland, &c., residing at Wyn-
5 yard, in the State of Tasmania, Common-
wealth of Australia, have invented certain
new and useful Improvements in and Relat-
ing to Ship - Ventilators and Connections
Thereto; and I do hereby declare the fol-
10 lowing to be a full, clear, and exact descrip-
tion of the invention, such as will enable
others skilled in the art to which it apper-
tains to make and use the same.

This invention relates to improvements in
15 ship construction, and provides means for
regulating ventilation, and for facilitating
prevention of sinking through collision or
events whereby hulls allow water ingress; if
20 fire occurs, extinguishing will be facilitated.
If a ship sinks it will, by the aid of these
improvements, be more easily raisable than
otherwise.

There are already inventions for closing
25 bulkhead doors and other apertures, intro-
ducing air or other gases, and expelling
water; but they have not covered the mat-
ters this invention deals with. It is par-
ticularly with the opening and closing of and
30 use of ventilators and air shafts and con-
nected parts that this invention deals.

This invention is best applied to steam
ships having means for closing not only
bulkhead and hatchway openings, but also
35 the engine room top, so that air or water
shall not pass in or out unless permitted.
The ship has a number of non-return sea
valves in its bottom, and means to allow ex-
pulsion of water therethrough to clear the
40 hull; and means for flooding compartments
or holds to provide against fire. The funnel
is preferably closable so that a large air
chamber may be produced below the closure.
Engine room closing means may utilize
45 known bulkhead door closing devices (with
appropriate modification) operable from a
predetermined point or points. Cabin side
light openings, and the like, are closable
against air and water. Other openings in
50 ship compartments must also be controllable.

With multiple deck ventilators which,
using a single cowl or top, supply air down to,
or pass it up from, different decks, or com-
partments, the value of improved closing
devices is considerable. Some ventilators
55 now used have no closing means; in other
cases the means are inadequate in emergen-

cies; the result is that just when time is most
precious, because of water entering the hull,
the air is allowed to escape, instead of being
locked in and increased in density to resist en-
60 try of water. Again, if fire rages, ordinary ven-
tilators admit air which promotes combustion;
but I provide means for cutting air off. When
water enters by a leak I may cause it to raise
65 floats and the latter to automatically close
ventilators; or I may in a known manner,
cause entering water to close an electric
circuit and the latter to cause ventilator
closing. By omitting some features, I still
70 retain novel means for opening and closing a
plurality of ventilator ports or tubes.

In the accompanying drawings a multiple
deck ventilator is illustrated.

Figure 1 is a side elevation, and Fig. 2 a
75 rear elevation. Fig. 3 is a diagram showing
arrangement, for discharging water shown as
having entered the hull through a hole
broken in its bottom. Part of each figure
is in vertical section. Fig. 4 indicates dia-
80 grammatically the means by which an alarm
is given when the floats rise. Fig. 5 shows
diagrammatically the means for indicating
which of the deck ports are open and which
are closed.

The space under each deck has ventilator
85 communication with the outer atmosphere
by ports shown closed in Fig. 1, and open in
Fig. 2. Any port may be closed leaving
the rest open; all will open or close together
90 when desired; opening and closing may be
effected from any deck; but, it is only from
the top, or a predetermined deck that the
vertical rod to which the port closing plates
95 are connected (adjustably) can be lowered,
when the pawl (or a catch provided) is in
locking or gripping position. In Fig. 3
several ventilator ports are shown closed,—
some by the rise of a float.

A indicates any suitable ventilator cowl,
or open top, B a closed top or adjustable
100 cap which, in some cases, screws on; C the
first or upper tube of the ventilator, D its
second tube of less diameter, and E its lower
tube of still less diameter.

F, G, and H are any decks, such as upper,
middle, and lower. There may be also as at
I (Fig. 3) an incomplete or boat deck.
This invention is applicable to more or
fewer decks than are shown.

The ship's bottom J is of any suitable con-
struction; it is shown cellular, with a hole or
fracture K.

L represents transverse bulkheads of which there are a suitable number. A lower bulkhead is shown fractured, water M, N, having simultaneously entered two compartments 5 of the ship.

Under open air space O, are compartments P, Q, R, having ventilator ports S, T, U; S and T are annular.

I do not limit the construction to port 10 closing plates V, W, shown, but these annular plates or collars are suitable. Rings a, b (from which the annular plates extend) fit close round ventilator tubes D, E.

X is a suitable port closing disk. Each 15 plate (with, at will, the aid of rubber or other packing) fits in place so as, when closed, to form a strong air tight joint. When any ventilator tube has a side opening, as at Y Fig. 3, the latter is closed as well as port S 20 by providing downward extensions or arms supporting a closing plate sleeve or ring Z.

There is a rack c on a rod d which extends from top to base within the ventilator tubing. This rod has in some cases (as 25 where weight is great) a plurality of racks, as one at each end. Each rack has gear to be operated manually or otherwise. Rod d is longitudinally movable and can (when its weight with connected parts allows) be 30 lifted by pushing upward any external plate V or W, or plate or disk X,—all rising because each is connected to said internal rod. Disk X is adjustably connected as by internally screwed collar e; and parts V, W 35 also adjustably connected as by internally screwed collars or nuts f and g, to the plates by suitable arms h, i. There are also adjustable nuts j, k or the like; rod d is provided with screw threaded parts or ferrules 40 l, m, n (which are either fixed or adjustable). But I may modify the arrangement of some of these details. Plates V, W, may be in sections, connected, and rings or collars a, b, may have inner packing. When com- 45 pressed air is to be supplied to tube C Fig. 2, it may enter as dotted at 20.

Mounted to project through the side of tube C is a spindle o fitted with suitable means, as wheel p or a handle or gear wheel, 50 for turning it. Pinion q engages rack c, and by turning part p (near which is ratchet wheel r adapted to be held by a strong pawl, catch, or locking device s) the rack c and rod d are moved or raised, but can not descend 55 or return till the catch is released or lifted. When release is effected the rod can fall and the ventilators open, but by individually operating any plate V, W, X, by rotating its respective internally threaded collars f, g 60 or e on the threaded portion of the rod on which said collar is mounted it can be moved up or down to open or close its port independently of other ports. If unusually much air is to be delivered (see Fig. 3) to a 65 compartment R, I close ports S and T; or

all ports may first be closed, and then plate X opened. Again, when air is to be delivered to compartment Q, but not to P or R, this is easily managed. The tops of tubes D, E, are in some cases extended higher, or parts a, b, extended lower than shown, to allow the closing means to be, when desired, raised higher than in Fig. 1 and still close their ports. Arms h, i have in some cases longer vertical members, not resting (when the ports are open) on tubes as in Fig. 2; but such rests usefully relieve rod d of weight. If a plate V, W or X (see Fig. 2) be adjusted or screwed up a short distance by hand, without closing its port, then when wheel p 70 is turned it will close such ventilator, leaving the rest open. t, u, v, indicate any suitable stops, which in some cases are provided to limit upward movement of plates V, W, X. The aforesaid construction occupies little 75 space within the tubing; it strengthens it, and greatly resists downward or upward pressure; it is free from delicate parts and springs; it can be readily kept clean; and inspection of all parts is easy. Each plate 80 V, W, X is removable, and replaceable, but can be permanently fixed for special use. When a ship is in port, removal of some parts may be an advantage. As shown the deck under sides are clear of projections; 85 this is important, ceilings usually being low. 90

I provide a suitable number of powerful air compressors or blowers w (Fig. 3) driven by suitable means, as steam power, or a dynamo x, the compressed air being delivered by suitable tubing y, and branches therefrom to different compartments of the ship, giving forced ventilation, or to establish sufficient air pressure in any compartment to drive out water which has entered, 100 and so to keep the vessel afloat. The hatches and like openings are closed against upward and downward pressure. Tube z enters pipe D; tube 1 enters compartment R on one side of a bulkhead, and tube 2 105 enters compartment R on the other side of that bulkhead. Pressure gages 3 are provided in all desired suitable positions; one is shown in Fig. 3. At suitable desired points valves are placed to allow air or 110 steam supply, or both, to be turned on or cut off. Among these are valves (operable from deck F) having handles or keys marked 4 which project permanently; or in some cases, are removable. Suitable check 115 or non-return valves (not shown) are provided in all compressed air or steam piping. The ship is fitted with suitable means of indicating increase and decrease in height of water in the hull. Taps as at 19 are provided on tubes 1, 2, to allow air to be delivered when desired to spaces P, Q. 120

Communication with steam supply or compressed air supply, is provided as by pipes 5, 6; the former joining tube y, passing 125

130

a check or other suitable valve so that when desired steam may be forced down pipes 1, 2. As however it is well known steam is a useful fire subduer, its use or that of water 5 in holds is not claimed. The directions in which air, steam or water move are shown by arrows in Fig. 3; air ports not having arrows are for the time being regarded as closed.

10 In Fig. 3 float 7 has risen and lifted rod *d*; 8 is a float case. By detaching a connection to or standard of the float shown as tube 9, the float may be removed. I use a sufficient number of floats, and of sea cocks or valves, 15 and do not so rely on though I may also use hole K for the expulsion of water. A sea valve is shown open at 10. It has any suitable construction; all such valves are placed under control (by suitable means not shown) 20 from a convenient distant point. These valves remain closed until pressure of air on the water to be expelled exceeds the pressure of the outer sea on the valve and at hole K.

25 Heavy losses occur to many passenger vessels notwithstanding double bottoms and bulkheads. An authority who states that every compartment (these are very numerous) in a vessel should be ventilated, adds 30 that "it is a golden rule never to make a doorway however good the system of securing water tightness may be, if it can be avoided; for as accidents from collision usually happen at unexpected moments, such 35 doors are often open at those times, and many a good ship, from no other cause, has foundered." Now the objections to leaving doors open, apply to ventilators. The ingress of water in bad weather through venti- 40 lator shafts is a source of danger in some ships. A battleship (the *Victoria*) well supplied with bulkheads and watertight compartments, sank in ten minutes in smooth water in daylight after receiving one 45 blow; turret and other high openings had not been closed and as water poured in, these helped the vessel to lose stability, the presence of a large crew being unavailing. Mer- 50 chantile ships are less suited than warships to withstand collisions; hence the need of spe- cial attention even to ventilator details.

55 By devices shown in Fig. 3 immediate action is promoted when water rushes into the hull, so as to counteract tendency to dangerous heeling over or listing. The de- 60 vices include electric circuits (of which parts are illustrated) for purposes below described. Thus wires 11 (communicating with each float, or float well) are arranged to ring a bell 12 when bilge water reaches a predetermined height. Wires 13 connected with and adapted to start the dynamo, or other means for causing supply of compressed air, are arranged in circuits closable at a predeter- 65 mined point as the bridge of the ship; a start-

ing circuit is in some cases completed automatically when bilge water rises to a pre-determined extent. Other electric wires may be (this is not claimed) arranged to cause ringing of a bell (as 14) when the heat 70 in a compartment exceeds a predetermined temperature. Suitable electrical connec- 75 tions for the foregoing effects can be readily effected by one skilled in that art.

To allow of ventilator ports being opened 75 by hand, in spite of the raising of rods *d*, is a great convenience in the daily life of a ship. But as a safeguard, positive evidence is pro- 80 vided when desired, at a suitable station, as above deck F, showing which ports are ac- 85 tually open or closed at a given moment. Electric circuits are accordingly arranged to light lamps or indicate at a station 15, each lamp or indicator representing by number or otherwise a particular ventilator port; wires 85 16 lead to the said ports, closing of the latter completing a circuit. When electric indica- 90 tion is not required, current is switched off. It can always be seen at a glance which ports need immediate attention. Port wires are 95 illustrated only at 17. Each alarm bell and indicator station is located where convenient; as on the bridge, or in the engine room.

Owing to their size and weight, bulkhead 95 doors are rarely operated otherwise than by hand. The time needed to close such a door may be under a minute; but at times of ex- 100 citement and of other deterrent factors, men are not at (nor will they go to) the doors; the same applies to ventilators. But with my 105 invention men need not go down to each ven- 110 tilator port. Not only is each vertical series of these ports closable from above—connec- 115 tions to simultaneously raise by power a plu- 120 rality of ventilator rods *d* are providable. These are not shown or claimed, but are in part diagrammatically represented by dotted line 18, Fig. 3. Many seamen neglect to take precautions against disaster, but then aids to safety are often inadequate. With the aids 125 above set forth, a few cool headed men may readily save a ship. But if a ship sinks—if, though equipped with these safeguards, they are not used—it is possible for divers, if able to reach wheels *p* to close ventilator ports, 130 which had been left open and which would otherwise be inaccessible. This would be a preliminary to forcing air into the hull to expel the water to raise the ship.

What I claim as my invention and desire 120 to secure by Letters Patent of the United States is:—

1. In a ship ventilator, an internal vertical rod, port closing plates connected thereto, gearing connected to the rod and extending 125 outside the ventilator, and means for actu- ating said gearing and thereby the rod whereby the movement of the plates will open and close respective ports.

2. In a ship ventilator, an internal vertical 130

rod having one or more port closing attachments and a rack thereon, in combination with a pinion upon a spindle which extends outside the ventilator, and means for turning and locking said spindle.

3. In a ship ventilator, a longitudinally movable internal vertical rod, one or more threaded sleeves engaging it, arms extending from the sleeves and one or more external 10 annular port closing plates connected to said arms.

4. In a ship ventilator, a longitudinally movable internal vertical rod having screw threaded portions or members in combination 15 with adjustable collars having attached thereto arms connecting to port closing plates.

5. In a ship ventilator, a rod having arms supporting annular port-closing means, and having also a port-closing disk, the said 20 means and disk being each independently adjustable on said rod.

6. A ship ventilator device comprising a ring or collar fitting closely around the outside of a ventilator tube, an annular plate 25 extending from the said ring, and arms extending from the plate to a supporting member within the tube.

7. The combination of decks having openings of different sizes therein, said openings 30 being in line with each other, ventilator tubing having sections of different sizes secured to said decks around said openings, an opening being left around the top of each tube except the highest one, movable plates for closing said 35 openings, means for moving said plates, and stops to limit the upward movement of said plates, substantially as described.

8. The combination of a ventilator tube, decks provided with ports, an internal rod 40 extending downward through a plurality of decks and having port-closing plates connected thereto, means for raising said rod and plates, and means above the upper deck to lock the rod in raised position, substantially 45 as described.

9. The combination of a series of decks having openings therethrough in line with 50 each other but of different sizes, sections of ventilator tubing, the lower ends of which are secured to the decks around said openings, openings being left between each deck and the sections of ventilator tubing attached to the deck below, an internal vertical rod

carrying means for closing the openings between the upper ends of said tubes and the 55 corresponding decks, and a float adapted to raise said rod, thereby closing the openings between the decks and the upper part of the sections of the ventilator tubing, substantially as described.

10. The combination with the decks of a ship having openings of different sizes arranged therein, ventilator tubes, each having its lower end secured to the deck around one of said openings, an opening being left between the upper end of said tubes (except the highest) and the corresponding deck, means for closing the openings between the upper ends of said tubes and the corresponding decks, a float adapted to be raised by bilge 65 water to actuate said means, and devices actuated by the rise of the float for giving an electric alarm, substantially as described.

11. The combination with the decks of a ship having openings therein of different 75 diameters, said openings being placed in a vertical line, tubes of different diameters, each having its lower end secured around the opening in the corresponding deck, but leaving a space between its upper end and the deck 80 next above, means for opening and closing the openings between the upper ends of the tubes and the corresponding decks, and means for supplying compressed air through said ventilator tubes to a predetermined 85 compartment of a ship, for the expulsion of water, substantially as described.

12. The combination with the decks of a ship having openings therein of different diameters arranged one above the other, ventilator tubes of different sizes, the lower end of which is secured around the opening in one of the decks and the upper end of which enters the opening in the deck above, but leaving a space therebetween, means for closing 95 any of said openings between the upper ends of the ventilator tubes and the corresponding deck, and means for indicating which of said spaces are closed and which are open, substantially as described.

In testimony whereof, I affix my signature in presence of two witnesses.

EDWIN ORLANDO BLACKWELL.
